UNITED STATES PATENT OFFICE

DUDLEY R. DALE, OF TOLEDO, OHIO, ASSIGNOR TO THE S. M. JONES COMPANY, OF TOLEDO,
OHIO, A CORPORATION OF OHIO

REEL

Application filed January 26, 1931. Serial No. 511,131.

This invention relates to a reel adapted for supporting rods or the like in successive positions while various operations are performed thereon by means of a lathe or other metal working machinery.

Heretofore, the reels used in operations of this kind have had long tubes through which the stock is fed, and inasmuch as the rods constituting the stock are often of great length, the insertion of the same in the tubes is an awkward procedure. The inconvenience of such a reel is particularly noticeable in manufacturing sucker rods of considerable length which must be inserted and removed by an endwise movement.

With the above conditions in mind, it is the object of the present invention to provide a reel support or stock rest in which the operation of inserting or removing the rods is greatly simplified, and more specifically to provide such a support with laterally or radially disposed slots and means for retaining the stock therein as it is worked upon.

The invention, in its preferred form will be more particularly explained in connection with the accompanying drawings, in which:

Fig. 1 is a side elevation of the invention in position for operation; Fig. 2 is a vertical transverse section taken on the line 2—2 of Fig. 1; Fig. 3 is a vertical transverse section on an enlarged scale taken substantially on the line 3—3 of Fig. 1; Fig. 4 is a side elevation of parts shown in Fig. 3; Fig. 5 is an enlarged detail sectional view taken on the line 5—5 of Fig. 3.

The invention is illustrated as adapted for use in connection with a metal working machine 7 having a number of chucks 8 to which the rods 9 are fed. The term "rod" as used in this specification includes any comparatively long piece of material to be worked upon.

The reel or stock rest for supporting the rods 9 includes a plurality of circular heads 10 secured to a single shaft 11, which is adapted to turn with the machine head 7, the several heads 10 being rotatably mounted in circular series of rollers 12. Each series of rollers 12 is mounted in a shell 13 which is supported by a standard 14 and which is

open at one side where it is provided with a shelf or table 15.

Each of the circular reel heads 10 is formed with a number of slots 16 corresponding to the number of chucks 8. These slots 16 extend inwardly from the periphery of the head 10 as shown in Fig. 3, and the bottoms thereof constitute rests on which the rods may be supported.

The reel heads 10 are disposed in spaced parallel relation and rock shafts or rods 17 are mounted therein. To each shaft 17, at one side of each head, there is secured a dog 18. A crank 19 is also secured to each shaft 17 adjacent one of the heads 10. The outer end 20 of each crank 19 is provided with a handle 21 in which a latch bolt 22 is mounted. A coil spring 23 within the handle 21 tends to project the bolt 22 into the head 10. The head is formed with two holes or recesses 24 and 25 for each bolt 22 so that by manipulation of the bolt by means of a knob 26 secured to its outer end the shaft may be locked with the dogs thereon in retracted or inoperative position, or in a position where they extend across the adjacent slots 16 to retain the rod 9 therein. For supporting sucker rods or the like, which are circular in cross section, the bottom of each slot and the opposed face of the dog together form a circular guide through which the rod may be fed.

In the operation of the reel or stock rest, the rods 9 are inserted by a lateral movement into successive slots 16 and the dogs 18 are moved into position to retain them while they are presented successively to the chucks 8 for various operations. These operations will be performed in the usual manner and as each rod completes the circuit about the shaft 11 it is released from the reel by retracting the dogs 18 which retain it, and the next rod is inserted therein. It is understood, of course, that all of the dogs for retaining a single rod 9 are secured to a single shaft or rod 17 so that they are moved into or out of position simultaneously by means of the handle 21.

It will be readily appreciated by those skilled in the art that the present invention permits the saving of a great deal of time in mounting the rods in the stock rest or reel

and in removing the same therefrom, especially when rods of considerable length are worked upon.

While I have shown and described the 5 preferred embodiment of my invention, it is obvious that various modifications may be made in the details thereof without departing materially from the scope of the invention as claimed.

10. What I claim is:

1. A reel of the class described, comprising a plurality of heads connected together in spaced relation and provided with laterally disposed rests for receiving rods to be 15 worked upon, the rests in each head being in alignment with corresponding rests in the other heads, a shaft adjacent each row of rests, and dogs secured to each shaft corresponding to the respective rests, each of said 20 shafts being independently adjustable to bring the dogs thereon simultaneously into or out of position to retain the rod on the rests.

2. A reel of the class described, comprising a plurality of heads connected together 25 in spaced relation and each provided with laterally disposed rests for receiving rods to be worked upon, the rests in each head being in alignment with corresponding rests in the other heads, and means movable into cooperative relation to each row of rests for retaining 30 the respective rods in position for the work to be performed, the retaining means for each rod being movable as an independent unit.

3. A reel of the class described, comprising a plurality of heads connected together in spaced relation and provided with laterally disposed rests for receiving rods to be 40 worked upon, the rests in each head being in alignment with corresponding rests in the other heads, dogs movable into operative position in opposed relation to said rests to form 45 guides for the rods, the dogs for each row of rests being connected to move as a unit, and means for locking each unit with its dogs in either operative or inoperative position.

4. A device of the character described, comprising a plurality of heads rigidly connected in coaxial spaced relation and provided with 50 rests for receiving rods to be worked upon, the rests in each head being in alignment with corresponding rests in the other heads, supports in which the respective heads are rotatably mounted, rock shafts mounted in said 55 heads parallel to the axis thereof, there being one such rock shaft adjacent each row of rests, dogs secured to each rock shaft adjacent to the respective heads and movable with the rock shaft into cooperative relation to the 60 adjacent rests to form means for guiding the rods longitudinally, and means adjacent to one of said heads for positively controlling the positions of the respective rock shafts.

5. The combination with a support, of a 65 reel rotatably mounted therein and provided

with rests arranged in a row parallel to the axis of the reel for receiving a rod to be worked upon, and a row of rigidly connected dogs carried by the reel and movable as a unit into or out of position to cooperate with said rests for guiding a rod longitudinally and maintaining it in a position substantially parallel to the axis of the reel.

6. The combination with a support, of a reel rotatably mounted therein and provided with rests arranged in a row parallel to the axis of the reel for receiving a rod to be worked upon, a member carried by the reel and rockable thereon, said member including a row of rigidly connected dogs movable by the rocking of said member into or out of position to cooperate with said rests for guiding a rod longitudinally and maintaining it in a position substantially parallel to the axis of the reel, and a detent carried by said member, said reel having means cooperating with said detent to lock said member with the dogs in operative or inoperative position.
